REFRIGERATOR CAR CONSTRUCTION

Walter P. Murphy, Chicago, Ill., assignor to
Standard Railway Equipment Manufacturing
Company, Chicago, Ill., a corporation of Delaware

Application July 29, 1940, Serial No. 348,156

4 Claims. (Cl. 62—19)

This invention relates to refrigerator cars used to transport perishable commodities at a predetermined temperature. The essential features of a refrigerator car are an insulated body to prevent or retard ingress of heat during warm weather and egress of heat during cold weather and a cooling means and a heating means to be used during warm and cold weather respectively.

The conventional end bunker car has the cooling means, preferably containers for a solid refrigerant, such as ice, or a liquid refrigerant, such as brine, disposed adjacent the end walls of the car. The lading is supported by foraminous racks arranged in spaced relation to the floor so that cold air may circulate from the cooling means under the lading. The cold air then seeps upwardly through the lading with a consequent cooling or refrigeration of said lading. The distance between the cooling means of a standard end bunker car is about 33 feet; the cold air must therefore travel more than 16 feet in order to reach the center part of the car. In many cases, the air all seeps through the lading in the end parts of the car and does not reach the center or, if it does reach the center, it has lost a considerable part of its refrigerating ability. Consequently, the center parts of standard and bunker refrigerator cars are commonly poorly refrigerated.

It is an object of the instant invention to provide a refrigerator car wherein the cold air circulates in a relatively short path for the purpose of overcoming the above-mentioned defects. I accomplish this by placing the cooling means adjacent the side walls of the car so that the maximum length of circulation is equal to the width of the car. It is a further object to balance the car by placing one cooling means between the doorway and an end wall and adjacent a side wall and the other cooling means between the doorway and the other end wall and adjacent the other side wall.

Another object of the invention is to maintain at a minimum the number of hatches used for loading the refrigerant. An excessive number of hatches, besides increasing the labor and expense of icing the car, constitute a serious source of heat leakage into the car on account of the inherent imperfections in the insulation of a movable door means.

Another object is to provide, as a cooling means, a bunker having an inclined grate to facilitate the distribution of refrigerant throughout the bunker. I design the grate so that the

highest part thereof is substantially below a hatch; the grate preferably extends downwardly therefrom to remote parts of the bunker.

Another object is to arrange the refrigerant bunker and grate so that they may be conveniently and easily assembled and so that the assembled bunker is a rigid structure.

Another object is to provide means for cooling the part of the lading adjacent the doorways of the car as will be hereinafter pointed out.

Other objects and advantages of my invention will be apparent from the following detailed description by referring to the accompanying drawings.

15 In the drawings:

Fig. 1 is a plan section of a refrigerator car which embodies my invention.

Fig. 2 is a longitudinal section of the car as indicated by line 2—2 of Fig. 1.

20 Fig. 3 is a transverse section on line 3—3 of Fig. 1.

Fig. 4 is an enlarged view of a portion of Fig. 3 showing the means of attaching the grate members.

25 Fig. 5 is a view similar to Fig. 4 showing a modified construction.

Fig. 6 is a section on line 6—6 of Fig. 5.

Fig. 7 is a perspective view of the grate support embodied in the car shown in Figs. 1 to 3.

30 Figs. 8 and 9 show modified forms of grate.

Fig. 10 is similar to a portion of Fig. 3 showing a modified form of drain pan.

Fig. 11 is a section, to an enlarged scale, on line 11 of Fig. 1.

35 Figs. 12 and 13 show modified forms of grate and positions of hatches.

The side walls 1 of the car shown are of the usual construction embodying side sills 2, side plates 3, side posts 5 extending between the sill 2 and plate 3, sheathing 6 forming the outer boundary of the wall, lining 8 forming the inner boundary and insulation 9 disposed between the sheathing 6 and lining 8. The corner construction comprises hollow posts 11 with the end

40 45 sheathing 12 being secured thereto and having corrugations 14 formed therein and arranged to extend substantially between the hollow posts 11. End lining 15 forms the inner boundary of the end walls 17. The roof 18 is supported by the side walls 1 and end walls 17, the roof comprising outer sheets 20, ceiling 21 and insulation 23. A doorway 24 is provided in each side wall 1, preferably midway between the end walls 17.

50 In the modification of my invention shown in the drawings, a refrigerant bunker 30 extends

between the doorway 31 and end wall 33 adjacent the side wall 34. Another bunker 36 extends between the doorway 37 and end wall 39 adjacent the side wall 40. The bunker 30 is included between a plurality of posts 42 adjacent the side wall 34 and a plurality of posts 43 spaced from the side wall 34. The posts 42 are rigidly bolted to the frame members 45. The posts 43 are secured to tie rods 48, 49; the tie rods 48 having their other ends attached to the side wall frame members 51 and the rods 49 having their other ends attached to the posts 42. The upper ends of the posts 43 are preferably inserted in pockets formed in the ceiling 21 and the lower ends of the posts 43 are maintained in spaced relation to the posts 42 by the grate supports as will be hereinafter described.

The corners of the bunker 30 are defined by vertically disposed angles 55. The walls of the bunker 30 are formed by foraminous material, such as the wire netting 56 shown, extending between the angles 55 and supported therebetween by the posts 42 and 43. An imperforate sheathing 58, preferably wood, is secured to the opposite sides of the posts 43 to form a bulkhead. Sheathing 59 also extends between the post 60 and the doorpost 62. The sheathings 58, 59, or bulkheads, are spaced from the ceiling 21 to form openings 63 and from the floor 65 to form openings 66. Air adjacent the bunker 30, being cooled and therefore densified by contact with the refrigerant, flows by reason of its greater density through the openings 66 into the space 68 between the floor rack 69 and floor 65. The air then flows upwardly through the lading compartment 71, thereby cooling the lading, and finally back to the bunker through the openings 63.

As shown in Fig. 3, a drain pan 75 is placed below the bunker 30 at a lower level than the upper surface of the floor 65 to catch liquid formed by the melting of refrigerant. The pan 75 is extended adjacent the doorway (see Fig. 11) so that cold air from the bunker may flow through the space 74 under the floor rack stringers 76 (also through the apertures 78) and seep upwardly through the lading disposed adjacent the doorway. Such air may also flow crosswise of the car and cool the lading extending between the doorways 31 and 37.

The grate 80 for supporting a refrigerant is preferably comprised of angle members 81 arranged with their included angles facing downwardly so that their upper sides form runners upon which ice may slide lengthwise of the bunker. The angle members 81 are preferably spaced apart to provide for drainage of melted refrigerant. In the modification shown in Figs. 1-3, the angle members 81 have their highest parts 83 disposed substantially midway between the ends of the bunker 30, the members 81 being inclined downwardly from the highest parts 83 toward said ends. A hatch 84 is provided in the roof 18 substantially above the highest parts 83 of the grate members 81 so that a refrigerant loaded through the hatch will slide to the ends of the bunker and eventually fill the entire bunker. The refrigerant may be either block or crushed ice and the inclination of the angle members 81 is preferably such that the ice slides of its own accord to the remote ends of the bunker. The horizontal angle members 86 are secured to the vertical angles 55 to resist the thrust of the refrigerant against the ends of the bunker.

5 The grate 80 is preferably supported by the unitary grate supports 90 shown in perspective in Fig. 7. The base portion 91 comprises a continuous angle 93 with oppositely facing clips 94 secured thereto for stability. The upright portions are spaced apart angles 96 rigidly secured to the base portion 91 and the upper portion is an inverted channel member 97 rigidly secured to the upright angles 96. Bolts 99 are inserted through the web 100 of the channel member 97 with their shanks 102 extending thereabove and their heads preferably welded to the under side of the web 100. The angle members 81 of the grate are disposed between the bolts 99, keepers 103 are inserted on the bolts 99 and nuts 105 are tightened against the keepers to securely clamp the angle members 81 in position. The supports 90 rest upon wooden blocks 106 placed in the pan 75 and slots 108 in the upright angles 96 accommodate the tie rods 49. The tie rods 49, when tight, grip the supports 90 between the posts 42, 43, which gripping, in combination with the angle members 81, maintains the grate supports in their upright positions.

20 Figs. 5 and 6 show a modified means for attaching the angle members 81 of the grate to the channel members 97 of the grate supports 90. Triangular web plates 115 are secured, preferably by welding, to the angle members 81. J-shape bolts 116 are inserted through apertures in the web plates 115 and secured, by nuts 118, to the channel members 97. Such an arrangement presents a smooth upper surface on the grate for the easy sliding of refrigerant.

25 Fig. 10 shows a section similar to a portion of Fig. 3 wherein the drain pan 122 is disposed at substantially the level of the floor 65 instead of being depressed like the pan 75 of Fig. 3. A relatively narrow gutter 123 is provided to drain off the melted refrigerant.

30 Fig. 8 is a view similar to a portion of Fig. 2 showing a modified form of grate. The hatch is positioned as in Fig. 2, i. e., substantially midway between an end wall and doorway. The grate 125 shown in Fig. 8 embodies a high part 126 substantially below the hatch, the grate having parts 128 sloping downwardly toward the ends thereof. The end parts 129 of the grate 125 are preferably substantially horizontal.

35 Fig. 9 shows relatively the same part of car as shown in Fig. 8. The part 135 of the grate 136 which is disposed below the hatch is inclined less than the end parts 138 of the grate.

40 In the modification shown in Fig. 12, two hatches 142, 143 are provided in the part of the roof 18 between an end wall and doorway. The grate 145 has high parts 146, 148 disposed below the hatches 142, 143 respectively. The grate 145 is inclined downwardly away from each high part 146, 148 so as to form a low part 149 at each end of the bunker and a low part 151 substantially midway between the ends of the bunker.

45 In the modification shown in Fig. 13, a hatch 155 is provided adjacent the end wall 156 and the high part 158 of the grate 159 is adjacent the end wall 156. The grate 159 is inclined downwardly continuously from the end wall 156 to the opposite end of the bunker so that ice loaded through the hatch 155 may slide to any part of the bunker.

50 The accompanying drawings illustrate the preferred form of the invention, though it is to be understood that the invention is not limited to the exact details of construction shown and de-

scribed, as it is obvious that various modifications thereof, within the scope of the claims, will occur to persons skilled in the art.

I claim:

1. In a refrigerator car having a roof, a relatively long refrigerant bunker below said roof, a hatch in said roof above said bunker, and a grate arranged to support a refrigerant in said bunker, said grate having its highest part disposed substantially below said hatch and being inclined downwardly from said highest part.

2. In a refrigerator car having a roof, a relatively long refrigerant bunker below said roof, a hatch in said roof above said bunker in spaced relation to the ends thereof, and a grate arranged to support a refrigerant in said bunker, said grate having its highest part disposed substantially below said hatch and being inclined downwardly from said highest part toward each end of the bunker.

3. In a refrigerator car having a roof, a relatively long refrigerant bunker below said roof, a hatch in said roof above said bunker adjacent one end thereof, and a grate arranged to support a refrigerant in said bunker, said grate having its highest part disposed substantially below said hatch and being inclined downwardly from said highest part toward the end of said bunker remote from said hatch.

4. In a refrigerator car having a roof, a relatively long refrigerant bunker below said roof, a hatch in said roof above said bunker, and a grate arranged to support a refrigerant in said bunker, said grate having its highest part disposed substantially below said hatch and being inclined downwardly from said highest part, said grate comprising runners extending lengthwise of said bunker for sliding a refrigerant to remote ends of the bunker.
